UNITED STATES PATENT OFFICE.

HARRY H. STEPHENS, OF GLEN ROCK, NEW JERSEY, ASSIGNOR TO GILLESPIE MOTOR COMPANY, OF PATERSON, NEW JERSEY, A CORPORATION OF DELAWARE

CENTRIFUGAL MACHINE.

1,412,145.

Specification of Letters Patent. Patented Apr. 11, 1922.

Application filed February 5, 1920. Serial No. 356,458.

To all whom it may concern:

Be it known that I, HARRY H. STEPHENS, a citizen of the United States, residing at Glen Rock, in the county of Bergen and 5 State of New Jersey, have invented certain new and useful Improvements in Centrifugal Machines, of which the following is a specification.

My present invention relates to improvements in centrifugal machines, particularly 10 of the type in which the rotating basket is carried on a rigidly supported vertical shaft.

One of the objects of my invention is to arrange the supports for such a basket in 15 such a manner that there will be no possibility of the lubricant from the bearings for the shaft getting into the basket, and yet at the same time constructing the machine so that it may be driven from above.

Another object of my invention is to provide such a machine with a construction 20 which will permit the ready removal of the basket from the machine, as will be necessary at times for purposes of repair or the like.

With these and other objects in view, my 25 invention consists in the combinations and arrangements hereinafter more fully described and specifically pointed out in the claims.

In the drawings, Figure 1 is a side elevation, partly in section, of one specific embodiment of my invention; Fig. 2 is a plan view of Fig. 1, and Fig. 3 is a fragmentary side elevation, partly in section, of a modification embodying my invention. Like reference characters indicate like parts in the several views.

In the arrangement shown in Figs. 1 and 2 a circular frame 10 is provided with a central, tubular structure 11, in the upper and lower portions of which respectively are arranged bearings 12 and 13 for a vertical shaft 14. The shaft 14 extends above the upper bearing 12, and to this upper end is 45 attached the portion 15 of a basket support 16 which carries a basket 17 of the usual type. It will be noted that the basket support 16 extends downwardly over the upper bearing 12 and preferably the vertical por-

tion of the basket support 16 is made solid, 50 so that there will be no possibility of any lubricant from the bearing 12 entering the basket.

The shaft 14 may be rotated in any desired manner, but, preferably, when electric

power is available, I utilize an electric motor to drive a vertical driving shaft 18 which, in the form illustrated in Figs. 1 and 2, will become the armature shaft. This shaft is mounted in suitable bearings in the 60 usual manner, and the motor frame 19, which carries these bearings, is attached to a bracket 20, which, in the form illustrated, is pivotally connected at 21 to the frame 10. A rotatable screw 22 passes through a nut 23 attached to a bracket 24, connected to the bracket 20, the other end of the screw 22 being rotatably connected to a pivotally mounted member 25 pivoted at 26 to the frame 10. Normally, bolts pass through the 70 bracket 20 and through the frame 10 to hold the bracket 20 rigidly in position, but when these bolts are removed a rotation of the screw 22 will turn the bracket 20 on the pivot 21 and thus swing the motor 19 and its 75 shaft 18 into a position which will permit the basket 17 to be moved upward vertically on the shaft 14 to be taken out of the frame 10.

In order to permit this ready removal, the 80 driving connections between the shaft 18 and the shaft 14 are arranged so that the shaft 18 may be swung out of its normal position without necessitating any care on the part of the operator. To this end I preferably provide a centrifugal friction clutch which has a driving member 26 connected to the shaft 18, the driving member 26 being provided with projections 27 which engage in recesses in radially movable members 28, 85 which rest in a cup 29 formed on the upper end of the member 15 of the basket support. The exterior of the members 28 is preferably covered with some friction material such as leather. When the motor 18 is rotated to 95 start the machine into operation, the engagement of the projections 27 with the members 28 causes the latter to rotate, and as the speed increases the members 28 are thrown outwardly to produce a driving pressure between them and the cup 29 to rotate the basket. If desired, suitable brake mechanism may be applied to the cup 29 to stop the basket's rotation.

With the form of friction drive illustrated, it will be obvious that as the bracket 20 is swung on its pivot the projections 27 will pass freely out of the openings in the members 28 with which they engage, and that similarly, when the motor is returned 105

110

to its normal position these projections may readily be engaged with the corresponding openings in the members 28.

If electric power is not available, then I 5 may substitute for the motor drive for the driving shaft a belt drive, such an arrangement being illustrated in Fig. 3. In this arrangement a driving pulley 30 is mounted on bearings on a shaft 31 which is rigidly 10 mounted in a bracket 32, which in turn is connected to the bracket 20. On the bracket 20 is an idler pulley bracket 32, which carries bearings for one or more idler pulleys 33, around which the driving belt passes, 15 usually from a driving shaft above the machine. The projections 27 in the arrangement shown in Fig. 3 are formed directly on the driving pulley, and the arrangement otherwise is the same as that described as 20 being illustrated in Figs. 1 and 2.

Many features of my invention may be varied within wide limits without departing from the spirit thereof, and I therefore do not wish to be limited to the specific embodiment of my invention which I have used 25 for purposes of illustration.

I claim:—

1. In a centrifugal machine, a vertical shaft, upper and lower bearings for said shaft, a basket support connected to said shaft above said upper bearing, a basket carried by said support and means for driving said shaft connected to the upper end thereof.

35 2. In a centrifugal machine, a vertical shaft, upper and lower bearings for said shaft, a basket support connected to said shaft above said upper bearing, said support extending downwardly to form a cover over 40 said upper bearing, a basket carried by said support and means for driving said shaft connected to the upper end thereof.

3. In a centrifugal machine, a frame, a vertical shaft, bearings for said shaft in said frame, a basket connected to said shaft above said bearings and located within said frame, a driving member above said vertical shaft and said basket and adapted to rotate said shaft, a support for said driving member movably connected to said frame, driving connections between said vertical shaft and said driving member, said support and said connections being constructed and arranged to permit said driving member 55 to be moved into a position to permit said basket to be moved vertically on said vertical shaft to remove said basket from said frame.

4. In a centrifugal machine, a frame, a vertical shaft, bearings for said shaft in said frame, a basket connected to said shaft above said bearings and located within said frame, a driving member above said vertical shaft and said basket, driving connections 65 between said vertical shaft and said driving

member, a bracket supporting said driving member, said bracket being pivotally connected to said frame and arranged to permit said driving member to be swung into a position to permit the vertically upward removal of said basket from said frame. 70

5. In a centrifugal machine, a frame, a vertical shaft, bearings for said shaft in said frame, a basket connected to said shaft above said bearings and located within said frame, a driving member above said vertical shaft and said basket, driving connections between said vertical shaft and said driving member, a bracket supporting said driving member, said bracket being pivotally connected to said frame and arranged to permit said driving member to be swung into a position to permit the vertically upward removal of said basket from said frame, and means to swing said bracket on its pivot. 80

6. In a centrifugal machine, a frame, a vertical shaft, upper and lower bearings therefor supported in said frame, a basket support connected to said shaft above said upper bearing and extending downwardly 90 to form a cover over said upper bearing, a basket on said support and within said frame, a driving member above said basket, driving connections between said driving member and said vertical shaft, a bracket 95 movably connected to said frame and supporting said driving member, said bracket and said driving connections being constructed and arranged to permit said driving member to be moved to permit the vertically upward removal of said basket from said frame. 100

7. In a centrifugal machine, a frame, a vertical shaft, bearings for said shaft in said frame, a basket connected to said shaft above said bearings and located within said frame, a driving member above said vertical shaft and said basket and adapted to rotate said shaft, a support for said driving member movably connected to said frame, a centrifugally operated friction clutch between said vertical shaft and said driving member, said support and said clutch being constructed and arranged to permit said driving member to be moved into a position to 105 permit said basket to be moved vertically on said vertical shaft to remove said basket from said frame. 110

8. In a centrifugal machine, a frame, a vertical shaft, bearings for said shaft in said frame, a basket connected to said shaft above said bearings and located within said frame, a driving member above said vertical shaft and said basket, a centrifugally operated friction clutch between said vertical 120 shaft and said driving member, a bracket supporting said driving member, said bracket being pivotally connected to said frame and arranged to permit said driving member to be swung into a position to per- 125 130

mit the vertically upward removal of said basket from said frame.

9. In a centrifugal machine, a frame, a vertical shaft, bearings for said shaft in said frame, a basket connected to said shaft above said bearings and located within said frame, a driving member above said vertical shaft and said basket, a centrifugally operated friction clutch between said vertical shaft and said driving member, a bracket supporting said driving member, said bracket being pivotally connected to said frame and arranged to permit said driving member to be swung into a position to permit the vertically upward removal of said basket from said frame, said clutch being arranged so that the swinging of said driving member will simultaneously disconnect the driving and the driven members of said clutch.
10. In a centrifugal machine, a frame, a vertical shaft journalled in said frame, a

basket having a support connected to said shaft above said frame and depending in said frame, the upper end of said basket support being provided with a clutch drum, a motor supported in alinement with said shaft and having a motor shaft, and means connected thereto adapted for frictionally connecting said motor shaft with said clutch drum.

11. In a centrifugal machine, a frame having bearings, a vertical shaft journalled in said bearings, a basket support connected to said vertical shaft above said bearings, a motor supported independently of said shaft, and in alinement therewith and having a shaft, a friction device on said motor shaft, and a cooperating friction device on said vertical shaft, whereby said motor shaft is adapted to be directly and frictionally clutched to said vertical shaft.

HARRY H. STEPHENS.
